PIKE POLE

Robert F. Lutd, Carlisle, Pa.

Application February 7, 1945, Serial No. 576,694

3 Claims. (Cl. 294—19)

1

This invention relates to pike poles designed for use in setting telephone, telegraph and power line poles. The present invention is concerned with improvements in the pike staff or body, and also in a guard for the spike, and in a spud for the base of the staff.

It is essential that a pike pole have considerable flexibility so that it can bend very substantially between its ends as the workman moves the lower end thereof inwardly toward the base of the pole being set. However, it must have sufficient resilience to straighten out when removed from use, and sufficient strength to avoid fracture or shattering. If a pike pole breaks, its broken, jagged ends or fragments can cause very serious injuries as it snaps into pieces. Yet the pike pole must be relatively light for convenience of transportation and to facilitate its handling by the lineman.

I have found that a pike pole made almost entirely of wood is unsatisfactory and dangerous, as pike poles are necessarily so long that when given small enough diameter to impart adequate flexibility, they are too readily subject to fracture. Also, a long wooden pole tends to warp. On the other hand, an all-metal pike pole is impracticable because it is too heavy. Furthermore, an all-metal pike pole subjects the workman to the danger of electric shock or even electrocution when setting poles adjacent live wires.

Therefore, it is the primary object of the present invention to devise a pike pole comprising both non-metallic and metallic sections, so designed and interconnected as to have adequate flexibility and also adequate strength. This is accomplished without utilizing too large a diameter and without use of too heavy parts.

Another danger to workmen is the sharp pike or spike itself, which when unguarded frequently causes severe wounds or lacerations of the flesh while being handled and transported. Guards have been proposed heretofore, but I know of none that has proved satisfactory. Some of them do not fully enclose the spike, and others can slip off sideways, thus in reality making the spike more dangerous than ever by giving the workmen a false sense of security, so to speak.

Therefore, it is another major object of this invention to provide a spike guard that affords full protection, and that can be easily removed or replaced, yet that cannot be inadvertently shifted to expose the spike.

A further important object of my invention resides in the provision of a spud or spur device for attachment to the base of the pike staff to

2

securely anchor the latter to the earth as it is manipulated during the pole-setting operation.

The foregoing and other objects of the present invention will clearly appear from a study of the following description when taken in conjunction with the accompanying drawings, wherein:

Figure 1 is a side elevational view, partially in section, of the complete pike pole assembly with guard in place, each main section being partially broken away to enable a showing of the entire device in a single view.

Figure 2, chiefly in central section, represents an enlarged view of the upper or spiked end of the pike pole of Figure 1.

Figure 3 is a similar enlargement of the rear or lower end of the pike pole of Figure 1.

Figure 4 is a view similar to Figure 1, but with diversified elevational and sectional showings of the various parts, and with the guard and the spud removed.

Figure 5 is a bottom plan view of the pike pole as seen looking towards the right hand end of Figure 3.

Figure 6 represents a cross-section taken on the plane of line 6—6, Figure 3.

Figure 7 is a fragmentary top plan view of the left hand end of Figure 2.

Figure 8 represents a cross-section taken substantially on the irregular line 8—8, Figure 2.

With continued reference to the drawings, a multi-section staff is designated in its entirety by the numeral 10. At its front or upper end it carries a sharpened spike 11, and at its base it carries a spud indicated generally by the numeral 12. A spike guard or enclosure, indicated in entirety by numeral 13, completes the assembly, it being understood that this guard is removed when the pike pole is to be put in use.

The staff 10 comprises an intermediate section 40 in the form of a hollow metal sleeve, preferably of steel and preferably of about one-half the length of the entire staff, cylindrical in cross-section. At its ends the sleeve is tapered internally, as shown at 15, for complementary fit with correspondingly tapered external surfaces of a pair of rods 16 and 17, these rods being so shaped that they are practically identical. The rods 16 and 17 are formed from wood, vulcanized fibre, or other suitable natural or synthetic material which

is strong and tough and at the same time is insulating or a non-conductor of electricity. Each rod has an integral reduced extension 18 fitted closely within an end of the sleeve 14, this penetration being such that, roughly, two-thirds of the sleeve remains entirely hollow. These exten-

sions and the sleeve 14 are held against separation and relative rotation by pins or rivets 20. Preferably, the member 17 is knurled to assist the workman in frictional grip.

At the ends of the sleeve 14, surrounding the 5 tapered zones 15, there are provided steel ferrules 21, preferably shrunk upon the sleeve for reinforcing and smoothing the joint. The lower ferrule also is of assistance in providing a grip for the workman's hands. In this connection, the 10 section 17 may have one or more holes 22, shaped as shown, for the insertion of plier handles or any similar element that may provide lifting elements that the workman may grasp to facilitate lifting and shifting of the pike pole.

The lowermost or base end of the section 17 is reduced, as shown in Figures 3 and 4, to receive a metal sleeve 23 that is pinned thereto by a rivet or the like 24. To this sleeve there is welded or otherwise integrally joined the metal spud 12, which comprises a plurality of prongs 25, pointed and arranged and sufficient in number to insure that each time the base of the pike pole is shifted and set down one or more of the prongs will bite into the earth and hold the base in its new position. The shape of these prongs also permits ready withdrawal and shifting of the spud, and the means of attachment affords permanence.

The upper section 16 is likewise reduced, as seen 30 in Figures 2 and 4, to receive a metal sleeve 26, pinned thereto by a rivet or the like 27. This rivet also passes through a shank portion 28 of the spike 11, the shank portion being firmly fitted into the reduced extension. The sleeve 26 is capped by a heavy metal disk 30, welded thereto as shown, or made integral therewith in any suitable manner. The shank 28 preferably is welded, as shown 35 in Figure 2, to the disk 30, through which it projects in close confinement. The spike, therefore, is very rigidly and sturdily joined to the staff at a point where flexibility is undesirable.

The disk 30 is flush peripherally with the sleeve 26, and has an endless annular groove 31. The 40 previously mentioned guard 13 is in the form of a sleeve 32 closed at one end by a disk 33 (which may be welded thereto or formed in one piece therewith), and which telescopes freely over the disk 30 and a portion of the sleeve 26. It may be reinforced at its open end by a tightly fitted band 34. The sleeve 32 is slotted longitudinally at 45 35, immediately adjacent this slot there being a spring finger 36, attached to the sleeve 32 by rivets or in any other conventional manner. The free end 37 of the finger is bent into U-shape, or any other suitable shape to obtain the desired result, namely, of providing yielding latching cooperation between the member 36 and the sleeve 26, as permitted by the slot 35.

From the preceding paragraph it will be seen 50 that the guard 13 may be pushed into latched position regardless of the angular relationship between the guard and the pike pole staff, and that there is no possibility of the guard being accidentally removed or displaced to cause injury to the 55 workmen by the spike 11.

In further explanation, after complete exposition, let us assume that the pike pole assembly approximates sixteen feet in entire length. As an example, the total length of the steel sleeve 14 70

may be about eight feet. The non-metallic shafts 16, 17 may be five or six feet long, each having a reduced section extending into the metal sleeve about one or two feet, and riveted thereto. The spike and the spud are very securely affixed, and between them there is an elongated zone of such strength and flexibility as to preclude rupture or shattering of the staff while imparting to the staff an almost measured and predetermined amount of flexibility.

The foregoing dimensions are not critical, but roughly they closely approximate the desirable dimensions of a multi-sectional pike pole, determined by study as well as by trial and error.

15 Having disclosed my invention, I wish to be limited, as is customary, only by a reasonably liberal interpretation of the following claims.

What is claimed is:

1. In a pike pole, an elongated metal sleeve, a 20 pair of rods of fibrous material having bodies of substantially the same thickness as the external diameter of said sleeve and having reduced portions extending into the sleeve ends, and means interlocking said sleeve ends and said reduced portions, said sleeve ends having short internally tapered portions effecting a reduction of metal thickness towards their circular entrance edges, and said rods having complementary tapered surfaces.

2. In a pike pole, an elongated metal sleeve, a 25 pair of rods of fibrous material having bodies of substantially the same thickness as the external diameter of said sleeve and having reduced portions extending into the sleeve ends, means interlocking said sleeve ends and said reduced portions, and a ferrule tightly fitted to each end of said sleeve.

3. In a pike pole comprising a staff having a 30 sharp spike fitted coaxially to one end thereof, 40 and a detachable guard designed to render said spike harmless, said guard and said staff embodying complementary interconnecting means preventing accidental movement of said guard to expose the sharp end of the spike, said interconnecting means comprising an annular channel on the staff and a finger on said guard yieldingly urged into said channel whereby the guard may be quickly telescoped into latched connection with said staff.
